(57) **CLAIM**

The ornamental design for a robotic device, as shown and described.

DESCRIPTION

FIG. 1 is a isometric view of a robotic device in accordance with the new design;

FIG. 2 is a back view thereof;

FIG. 3 is a front view thereof;

FIG. 4 is a side view thereof;

FIG. 5 is a side view thereof;

FIG. 6 is a top view thereof; and,

FIG. 7 is a bottom view thereof.

The broken lines in FIGS. 1-7 are for the purpose of showing environmental structure and form no part of the claimed design.
